UNITED STATES PATENT OFFICE.

WERNER L. WIRSING, OF STUTTGART, ARKANSAS.

MANURE-LOADER.

1,165,642.

Specification of Letters Patent. Patented Dec. 28, 1915.

Application filed May 27, 1914. Serial No. 841,321.

To all whom it may concern:

Be it known that I, WERNER L. WIRSING, a citizen of the United States, residing at Stuttgart, in the county of Arkansas and State of Arkansas, have invented certain new and useful Improvements in Manure-Loaders, of which the following is a specification, reference being had to the accompanying drawings.

10 This invention relates to manure loaders. The object of the invention is to provide a thoroughly practical and highly efficient apparatus of this character which will remove manure from a pile and discharge it 15 into a wagon or onto any desired site, the manner in which the parts are constructed and coöperate being such as to secure the highest efficiency in use with the minimum output of power, and with practically no 20 danger of the mechanism becoming deranged from long-continued use.

With the above and other objects in view, as will appear as the nature of the invention is better understood, the same consists 25 in the novel construction and combination of parts of a manure loader, as will be hereinafter fully described and claimed.

In the accompanying drawings, forming a part of this specification, and in which like 30 characters of reference designate corresponding parts: Figure 1 is a side elevational view of a manure loader constructed in accordance with an embodiment of my invention; Fig. 2 is a top plan view of the device as herein disclosed; Fig. 3 is a sectional view taken substantially on the line 3—3 of Fig. 2; Fig. 4 is a sectional view taken substantially on the line 4—4 of Fig. 3; Fig. 5 is an enlarged sectional view taken substantially on the line 5—5 of Fig. 1; Fig. 6 is an enlarged sectional view taken substantially on the line 6—6 of Fig. 1; Fig. 7 is an enlarged sectional view taken substantially on the line 7—7 of Fig. 2; Fig. 8 is a sectional view taken substantially on the line 8—8 of Fig. 7; Fig. 9 is a sectional view taken substantially on the line 9—9 of Fig. 7; Fig. 10 is an enlarged fragmentary elevational view of the reversing mechanism herein included; Fig. 11 is an enlarged sectional view taken substantially on the line 11—11 of Fig. 2; and Fig. 12 is a detailed sectional view of the scoop locking means herein included.

55 Referring to the drawings, 1 designates a platform upon which the mechanism is sup-

ported. This platform is carried by a wheeled frame of any preferred construction, the rear wheels of which will, by preference, be power driven, thus to dispense 60 with the use of horses in drawing the machine over the ground.

Arranged on the platform is a scoop 2, the front end of which is open, and the sides and rear end of which are closed. The 65 under edges of the sides 3 of the scoop are formed with inturned guides 4, which are engaged by a sliding bottom 5, a cross brace 6 secured to the bottom and overlapping the guides at its ends, serving to prevent the 70 bottom from rising. The rear wall 7 of the scoop is provided with a series of orifices in which are disposed the shanks of rakes 8, which are of the usual or any preferred construction, and of which, in the present instance, six are shown. The forward ends of 75 these rakes are secured by a six-throw crank shaft 9, the cranks of which are so arranged that when three of the rakes are raised to take a fresh purchase on the manure the 80 other three are lowered so as to draw the manure on to the bottom. One end of the crank shaft is journaled Fig. 3 in a bearing 10 adjustably secured to one of the sides 3, while the other end is journaled in a similar 85 bearing 11 and projects beyond the same and has secured to it a sprocket wheel 12. The sprocket wheel is engaged by a sprocket chain 13 which passes rearwardly, and diagonally across the platform and engages a 90 sprocket wheel 14 carried by a shaft 15 journaled in a bearing 16 slidably mounted upon the base. This bearing 16 comprises two standards 17 carried by a base 18, projected from the front and rear of which are lateral 95 arms 19 that engage guides 20 secured to the platform. One of the standards has connected with it one end of a rod 21, the other end of which is connected with a crank shaft 22 secured to the rear end of the platform, 100 and which, upon being manipulated, will impart a reciprocatory motion to the standards, thus to move a gear wheel 23 carried by the shaft 15 into and out of engagement with a pinion 24 journaled upon a standard 105 25 secured to the platform.

Rigidly secured at the forward ends of the sides of the scoop or bucket adjacent to their rear ends are three arms 26, 27, and 28, the arm 27 being secured to the right hand side of the scoop, when the latter is viewed from the front of the machine, and the other

two arms secured to the left hand side of the scoop. The rear ends of these arms are rigidly bolted to one leaf of a hinge 29, the other leaf of which is rigid with a worm wheel or table 30 carried by the lower end 5 of a vertical shaft 31, mounted in the bearing 32 at the base of the frame, the upper end of the shaft being mounted in a bearing formed in a bracket 33 carried by a 10 standard 34 rising from one side of the platform. The worm wheel engages a worm 35 carried by a shaft 36 mounted in bearings 37 rigid to the platform, and on the shaft 36 is a sprocket wheel 38 that is engaged by 15 a sprocket chain 39 that passes around a sprocket wheel 40 carried by a rock shaft 41 loosely mounted in a standard 42 secured to the platform.

Secured to the rear portion of the 20 platform, and adjacent each side thereof, are two brackets 43 and 44 carrying bearings 45 in which is journaled a main drive shaft 46, that is driven from any suitable source of power, such as a gasolene engine or the like. 25 Carried by the shaft 46 is a gear 47 which meshes with the pinion 24 and thereby drives the latter to cause it to actuate the gear 23 and thus the sprocket chain 13, the motion of the latter being transmitted to the 30 six throw crank shaft 9, whereupon the rakes will have imparted to them a reciprocatory motion, thus to cause them to grasp the manure and draw it onto the bottom of the scoop. As stated, the sprocket chain 13 35 extends diagonally across the platform, and in order to cause it to remain in operative engagement with the two sprocket wheels 12 and 38, a series of guides 48 are employed which are secured to the shaft 31, arm 28 and 40 the scoop 2. This means of guiding the sprocket chain 13 will be found efficient for the purpose designed, but as will be understood, any other arrangement to secure the same result may be adopted without departing 45 from the spirit of the invention.

The main drive shaft carries two spaced gears 49, which, in conjunction with the gear 50 carried by the rock shaft 41, constitutes a differential gear for reversing the 50 direction of rotation of the worm shaft 36 so as to drive the worm wheel 30 in opposite directions, and thus cause the scoop to swing through the arc of a circle in order to distribute the manure properly over the receptacle to receive it.

Secured to the rear end of the bottom 5 is a cable 51 the lower lead of which passes to the rear end of the machine and around a drum shaft 52, the upper lead of the cable 60 being passed around a sheave 53 carried by a link 54 pivotally connected with the rear wall of the scoop, and thence to a drum shaft 55 at the rear end of the machine. One end of each of these shafts is journaled 65 in suitable bearings formed in the bracket

44, the other end of the shafts being arranged for sliding movement in slotted bearings 56 and 57 formed in a plate 58 supported by a bracket 59 rigidly secured to the platform. The drum shaft 52 carries a pinion 60, and the drum shaft 55 a similar pinion 61, and these are engaged alternately to be brought into engagement with a gear 62 on the main drive shaft, the shifting of the drum shaft 52 to bring its pinion into mesh with the gear 62 being accomplished by a lever 63 pivoted to the plate, and connected by a rod 64 with the shaft. The drum shaft 55 is moved to and from the gear 62 by a lever 65 carried by an arm 66 secured to the plate 58, and connected with the shaft by a rod 67. From this arrangement it will be seen that when the pinion on the drum shaft is in engagement with the gear 62, the upper lead of the cable will be wound upon the shaft and thus project the bottom of the scoop, and upon releasing the pinion 55 and locking the pinion 60 into engagement with the gear, the bottom of the scoop will be moved rearwardly, thus to discharge its load.

As is common with apparatus of this character, means is provided whereby when the scoop has been filled with manure or other material, it shall be raised and held in lifted position until it has reached the point where the contents are to be discharged, whereupon the scoop is dropped and the bottom retracted for that purpose.

The means for causing the raising of the 100 scoop comprises a drum shaft 68 one end of which is journaled in a bearing 69 carried by the bracket 43, and the other end of which is pivoted in a rock arm 70 carried by a bracket 71 supported by the platform. 105 The bracket is provided at its upper end with rack teeth 72 that are designed to be engaged by a spring pressed latch 73 carried by the rocking lever whereby a pinion 74 carried by the drum shaft 68 may be 110 moved into or out of locking engagement with the gear 47 of the drive shaft.

The rear end of the scoop has secured to it one end of a bar 75, the other end of which has connected with it a sheave 76, and through this sheave passes a cable 77 which is secured at one end to the standard 34, and the other end to the drum shaft 68. It will be seen that when the rock arm 70 is moved to lock the pinion 74 into engagement with the gear 47, that a backward pull will be imparted to the cable 77, thereby lifting the scoop, and upon the pinion being disengaged the scoop will of its own weight drop into its original position, whereupon 125 the mechanism for actuating the bottom may be manipulated to cause the load on the scoop to be discharged.

In order to maintain the scoop 2 in elevated position after the drum shaft 68 has 130

been disconnected from the gear 47 of the drive shaft, I employ the clamping member 78 pivotally supported between the upstanding spaced ears of a bracket 79 suitably secured to the upper surface of the bracket 33, the cable 77 passing between the ears of the bracket 79 and below the clamping member 78. The clamp 78 is operated in a manner which is believed to be self-evident.

19 From the foregoing description, it is thought to be obvious that a loader constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the particulars and spirit thereof and for which reason I do not wish to be understood as limiting myself to the precise arrangement and formation of the several parts herein shown in carrying out my invention in practice.

25 What I claim and desire to secure by Letters Patent is:—

1. A device of the character described comprising a frame, a scoop supported thereby and mounted for movement in a vertical direction and in a horizontal direction, a movable bottom for said scoop, a flexible member secured intermediate its length to the movable bottom and loosely

engaged with the scoop at substantially a 35 stationary point, and means coacting with the flexible member at points opposite to its connection with the movable bottom for imparting reverse movement to said flexible connection whereby the movable bottom 40 may be adjusted into either a closed or open position.

2. A device of the character described comprising a frame, a scoop supported thereby for movement in a vertical direction 45 and in a horizontal direction, a crank shaft disposed transversely of the scoop above the bottom thereof, rakes disposed longitudinally of the scoop and operatively engaged with the crank shaft, a source of 50 power fixed relative to the frame, a flexible connection between the crank shaft and the source of power whereby said crank shaft may be rotated irrespective of the vertical or horizontal adjustment of the scoop, a 55 guide for the flexible member carried by the scoop at a point rearwardly of the crank shaft, and a second guide for the flexible member carried by the frame and positioned at substantially the axial center of the horizontal movement of the scoop.

In testimony whereof I hereunto affix my signature in the presence of two witnesses.

WERNER L. WIRSING.
